HAND PUPPET

Elsa Foster, 306 W. 75th St., New York, N.Y.

Continuation of application Ser. No. 58,552, Dec. 4, 1959

This application July 10, 1961, Ser. No. 66,260

Term of patent 14 years

(Cl. D34—2)

FIG.1

FIGURE 3 is a three-quarter front view of the puppet of FIGURE 1, showing the head manipulated down to one side and one ear down over one eye.

The characteristic feature of my design resides in the almost complete encirclement of the eyes by eyelashes of reversed curvature.

This application is a continuation of my prior co-pending application D. 58,552, filed December 4, 1959, and now abandoned.

I claim:

The ornamental design for a hand puppet, as shown and described.
